UNITED STATES PATENT OFFICE

ABRAHAM ISAACSON, OF LOS ANGELES, CALIFORNIA

BOX LABEL

Application filed October 10, 1928. Serial No. 311,568.

My invention relates to labels as used for identifying the merchandise contained in a box or other receptacle, and while the invention is primarily designed for embodiment in boxes to contain shoes, the principles thereof may be carried out in the manufacture of boxes and labels intended to contain various other articles of merchandise.

At the present time it is the custom with 10 retailers of shoes not to deliver or hand to the purchaser the shoes in the box but to retain the box and merely wrap the shoes in paper. As a consequence, the retailers accumulate large quantities of shoe boxes, and 15 which as now labeled preclude their reuse for shoes other than those possessing the same characteristics as the original in respect to size, color, etc.

It is a purpose of my invention, therefore, 20 to provide a label for shoe boxes which is capable of being readily applied to and removed from the box without in any way disfiguring or otherwise rendering the box unfit for reuse to hold shoes different than 25 those it originally contained.

I will describe only one form of label and box embodying my invention and will then point out the novel features in claims.

In the accompanying drawing:

30 Figure 1 is a view showing in fragmentary perspective a box having applied thereto one form of label embodying my invention;

Fig. 2 is a vertical sectional view transversely through the box for illustrating the manner and means of attaching the label to the box;

Fig. 3 is an enlarged vertical sectional view taken on the line 3-3 of Fig. 1; and

40 Fig. 4 is a horizontal sectional view taken on the line 4-4 of Fig. 1.

In the adaptation of my invention to a shoe box, the conventional construction of box may be employed, it being necessary 45 only to provide openings in the box through which the identifying label may be extended. As shown in Figs. 1 and 2, the box comprises the conventional body 15 and top 16, the former being provided with a pair of slots 50 17 in the sides thereof at points adjacent

one end of the box. Through these slots a strip 18 of paper, fabric, or any other flexible material is extended so that the ends of the strip are disposed at the inner side of the box, the intermediate portion of the strip or that portion disposed at the outer side of the box bearing the usual identifying indicia for shoes, such as is illustrated in Fig. 1. Thus, a strip of material with its indicia constitutes the label for identifying the shoes or other merchandise contained in the box.

The label or strip 18 is removably secured to the box by the provision of a means which, in the present instance, comprises a U-shaped member formed of leather or other suitable material having one portion 19 permanently secured to the inner side of the box in any suitable manner such as by stitching, as illustrated. The other portion 20 remains unattached in respect to the box and thus functions as a tab. The portion 19 is provided with the head element 21 of a snap fastener, the tab 20 being provided with a socket element 22 of the fastening member, and which is adapted to engage the head element for detachably securing the tab in the closed position illustrated in Fig. 3.

In the applied position of the label strip 18, the ends of the strip are extended between the portions 19 and 20 and are disposed in overlapped relation with respect to each other, such overlapped portions being provided with registering openings to accommodate the head element 21 so that by moving the socket element 22 into engagement therewith, the ends of the label strip are secured to each other and to the box so as to maintain the strip against accidental displacement. It will, of course, be understood that to remove the label strip it is only necessary to free the tab 20 when the strip ends can be removed from the head element 21.

In practice, the descriptive indicia upon the outer side of the label strip 18 should correspond to the particular shoes contained in the box, and if these shoes are removed and another pair substituted of a different description, it will be manifest that the label strip can be easily removed and a new one substituted having descriptive indicia corre-

sponding to the new shoes placed in the box. Thus, the box may be used indefinitely, and each pair of shoes properly identified by the label, the application and removal of the label strip in no way disfiguring or otherwise rendering the box unfit for reuse.

5 I have found in practice that it is not necessary to form the ends of the strip 18 with openings to receive the head element 21 of the fastener, as the element 21 can be forced through the strip ends by movement of the socket element 22 into engagement with the head element.

10 Although I have herein shown and described only one form of label and box embodying my invention, it is to be understood that various changes and modifications may be made herein without departing from the spirit of the invention and the spirit and 15 scope of the appended claims.

20 I claim:

1. In combination, a box having openings therein, a label extended through the openings so as to have a portion of the label presented to the outer side of the box, and means for detachably securing the label to the box.

25 2. In combination, a box having openings therein, a label extended through the openings so as to have a portion of the label presented to the outer side of the box, and means on the inner side of the box for detachably securing the label to the box.

30 3. In combination, a box having openings therein, a label extended through the openings so as to have a portion of the label presented to the outer side of the box, and means for detachably securing the label to the box comprising complemental fastening elements one fixedly secured to the box and the other 35 movable to engage and disengage the first element.

40 4. In combination, a box label comprising a strip of flexible material, means for clamping the strip in loop form comprising a member of flexible material having two portions relatively movable, and a separable fastener having the two elements thereof secured respectively to the two portions of said member.

45 5. In combination, a box having openings therein, a label comprising a strip of flexible material extended through the openings so as to have a portion of the strip presented to the outer side of the box and the ends of the strip disposed at the inner side of the box, a flexible U-shaped member having one portion secured to the inner side of the box, and a separable fastener having the two elements thereof secured, respectively, to the ends of the member, the ends of the label strip being received between said portions so that by 55 causing the fastener elements to engage each other the strip ends will be secured by the fastener.

60 6. In combination, a box having openings

therein, a label strip extending through the openings to assume a loop form with a portion of the strip presented to the outer side of the box and to lie flat thereagainst, and means for detachably securing the label strip in loop form.

65 7. In combination, a box having openings therein, a label comprising a strip of flexible material extended through the openings so as to have a portion of the strip presented to the outer side of the box and the ends of the strip disposed at the inner side of the box, and means at the inner side of the box engaging the ends of the strip for detachably securing the strip to the box.

70 Signed at Los Angeles in the county of Los Angeles and State of California this first day of October, A. D. 1928.
